(57) **CLAIM**

The ornamental design for a class C trailer hitch flag holder, as shown and described.

DESCRIPTION

FIG. 1 is a perspective view of the class C trailer hitch flag holder of the instant invention;

FIG. 2 is a left side view thereof;

FIG. 3 is a right side view thereof;

FIG. 4 is a front view thereof;

FIG. 5 is a rear view thereof;

FIG. 6 is an enlarged top view thereof;

FIG. 7 is an enlarged bottom view thereof;

FIG. 8 is a perspective view of the lower portion of the class C trailer hitch flag holder of FIG. 1 shown in an unassembled position;

FIG. 9 is a perspective view of the upper portion of the design of FIG. 1 shown in an unassembled position;

FIG. 10 is a perspective view of the inner flag clasp of the design of FIG. 1 shown unassembled from the upper portion; and,

FIG. 11 is an enlarged top view of the assembled upper portion of the class C trailer hitch flag holder shown in FIGS. 9 and 10.

The broken lines shown in the figures represent unclaimed environmental subject matter and form no part of the claimed design.
